UNITED STATES PATENT OFFICE.

WILLIAM S. GODWIN, OF NEW YORK, AND CHARLES I. WILLIAMS, OF UTICA, NEW YORK.

PLASTIC-MOLDING MACHINE.

No. 829,712.

Specification of Letters Patent.

Patented Aug. 28, 1906.

Application filed February 2, 1905. Serial No. 243,792.

To all whom it may concern:

Be it known that we, WILLIAM S. GODWIN, a resident of the borough of Brooklyn, city of New York, county of Kings, State of New York, and CHARLES I. WILLIAMS, a resident of the city of Utica, county of Oneida, State of New York, citizens of the United States of America, have invented Improvements in Plastic Molding-Machines, of which the following is a specification.

This invention relates to that class of molding-machines such as shown in United States Patent No. 783,516, dated February 28, 1905, which machines are particularly adapted for compressing plastic material into blocks.

The object of this invention is to improve the construction of such machines so as to secure a better, surer, and steadier feed of some of the principal operating parts of the machine, particularly the revoluble mold-table and compression-plungers; to obtain a better lubrication of said plungers; to secure a more rapid and simple ejection of the pressed blocks from the molds to the conveyer which receives them, and to improve other constructional features, as set forth hereinafter.

In the accompanying drawings, Figure 1 is a plan view, partly broken away, of our improved machine. Fig. 2 is a vertical central section on the line 2 2, Fig. 1, also with parts broken away. Fig. 3 is a plan view of the mold-table and its operating mechanism, the compression-plungers, feed-hoppers, and ejector mechanism removed, part of the table being broken away to better illustrate the interior construction. Fig. 4 is a sectional view through the center of three molds in the mold-table or platform and shows them opposite an ejector, filling-hopper, and compression-plungers. Fig. 5 is a vertical section of half the mold-table and frame, showing the cam mechanism for rotating the table. Fig. 6 is a sectional detail of the lubricating-arm; and Fig. 7 is a sectional view on the line 7 7, Fig. 6; and Fig. 8 is a detail of the driving-pawl-disengaging lever.

The machine of this invention is what is known as a "duplex" machine—that is, one in which two molds are filled with the material, two molds undergo the compression action, and two molds have the compressed blocks ejected from them simultaneously. Hence the filling-hoppers H H, two compressing-

cylinders C C, and two ejectors E E are provided and are preferably located around a common axis, all mounted in suitable framing straddling the circular mold-table M. This mold-table rotates on circularly-arranged tracks t t' on the framing or base F of the machine. The table M, in view of the duplex arrangement hereinbefore referred to, must be caused to take an intermittent revolving motion about its axis, each mold stopping successively beneath a filling-hopper, between compressing-plungers, and below an ejector of each duplex set once in a complete revolution of the table. To secure this intermittent revolving motion, we mount in suitable bearings at the side of the frame F a suitable cam-wheel C', Fig. 5, having a cam-groove c, in which is guided a roller r, mounted on a lever-arm a, at one end pivoted to the frame at a' and at the other end to a horizontal connecting-rod R, through a stud a'. The free end of the connecting-rod R is attached to one arm of a duplex latch mechanism which rotates around a stud S on the axis of the machine.

A centrally-located pivoted arm 60, Fig. 3, is provided with latches 61 at opposite ends, connected by links 62 63 to a short pivoting link 64, so that one will follow the movement of the other. Below one of the latches 61 a bell-crank lever 65 is pivoted to the frame (see Fig. 8) in such a position that the lever 65 is adapted to throw said latch out of engagement with the notched inner circumference of the table M after the latter has been moved into a correct position, so that then the rod R, previously described, can return the arm 60 into a position to engage the table at a different and following point. A cam projection 68 on the cam C', to be hereinafter described, operates said bell-crank lever 65 at stated and proper intervals through the medium of the lever 67 and rod 66, Fig. 5. The cam-groove c in the cam-wheel C' is so shaped that the rod will be actuated at first slowly, to start the table M from its position of rest with one mold under its hopper, accelerated in its motion while traveling toward its next position, between the compression-plungers; but just before reaching these plungers its speed is slackened until it is almost nil, when nearly in a line with the plungers, remaining at absolute rest during the period in which

the plungers enter the mold, compress the material therein, and withdraw therefrom. Motion is imparted to the cam by the main shaft 1 and driving-pulley 2. In order to aid 5 the cam toward the end of the rod's stroke in stopping the table, which is heavy, and therefore has great inertia, we may bolt a spring and hydraulic stop-cylinder (see Fig. 3) to the frame of the machine, in which case we 10 fasten to the periphery of the table M, at equal distances apart, blocks 4, projecting slightly beyond the periphery of the table.

The hydraulic cylinder 3 has a barrel-piston 5 of substantial length located within the cylinder, having an opening at one end through which a tapered rod 6, secured to the cylinder-head, may pass, so fitting the opening in the piston when the piston is in one position as to practically stopper the hole, such stoppering being gradually effected through the 20 entire stroke of the piston by reason of the taper of the rod. Within the barrel-piston 5 there is located a strong spring 7, tending always to return the piston in a direction tangential to and against the direction of motion of the mold-table M. A collar 8, secured to the piston, has a bent lever 9 pivoted to it at 9', which lever and collar are free to slide in an opening in the wall of the 25 cylinder 3 midway between its ends. A lever 10, pivoted to the frame F at 10', has one extremity located between the cylinder 3 and the short end of the lever 9, while its other end is located adjacent to the cam C', which 30 carries on its face a projection 11, adapted to act against this lever-arm. As the mold-table is nearing the end of a partial rotation referred to before, a block 4 abuts upon the 35 end of the bent lever 9, striking it, causing it 40 to displace the piston 5 in a direction tangential to and in the direction of motion of the table M. This causes the water behind the piston to be displaced through the opening stoppered by the rod 6, the stoppering, as 45 before stated, increasing as the piston moves farther in until altogether when the motion of the table has been correctly arrested by the cam-groove c and an auxiliary mold-table-locking means to be hereinafter 50 described. Before the table is again moved a step in its rotation, the cam 11 comes around, abuts upon the end of the lever 10 and causes its shorter end to throw the lever 9 to release said lever of the block 4 on the mold-table. 55 The spring 7 will obviously now return the barrel-piston to the other end of the cylinder.

The auxiliary locking mechanism heretofore referred to consists of a cam-shaft 12, rotated by elliptical gears 13 14, gear 13 being fast on its shaft 12 and connected thereto by an ordinary construction of safety break-pin 15, while gear 14 is mounted upon a parallel shaft 16 and connected with the main shaft 1 through beveled gears 17 18. On the 60 shaft 12 a segmental locking-arm 20 and two

cams 21 22 are secured. Bearings 23, secured to the frame F, are provided for the shaft 12. The periphery of the mold-table M is provided with pockets or recesses 24, similarly disposed upon the periphery of the 70 mold-table as are the blocks 4, heretofore described. When the mold-table has just about come into its correct position for the operation of the various feeding, pressing, and ejecting devices, the segmental arm 20 is 75 in a position with its lower edge above and adjacent to a recess 24. It is in this position that the elliptical gears give to the cam-shaft 12 its greatest speed, causing the segmental arm 20 to rapidly enter the recess 24 and aid 80 in correcting the proper position of the mold-table, thus serving to positively lock the table against any further movement until the segmental arm shall have been removed from the recess. 85

The hydraulic operating-valve V is provided with inlet and exhaust passages to the compression-cylinders C and must be actuated before the movement of the compression or ejecting plungers. For this purpose 90 two rods 25 26 are connected from the valve-casing V through bell-crank levers 27 28, having rollers at their lower ends adapted to rest upon and be actuated by the cams 21 22. Should the table through some error not correctly place the molds in line with the plungers, the segmental arm 20 obviously will not enter the recess 24, but instead will abut against the solid material of the table and be stopped, thus preventing further rotation of 100 the cam-shaft 12 and preventing any operation of the valve by the cams 21 and 22. It is because of this possible stoppage of the cam-shaft 12 that we locate the breaking-pin 15 between the cam-shaft 12 and gear 13. 105

Heretofore the ejectors E in this type of machine have been operatively connected with the compression-plungers by means of a single central hydraulic cylinder, piston, and piston-rod, to which the ends of the ejector-levers have been fastened, said hydraulic cylinder being used as a means for withdrawing the ejector and compression plungers from the molds. We have found that such construction does not allow uniform compression 115 of the blocks in oppositely-located compression positions. Therefore in this machine we have located near the central axis of the machine two cylinders 31 31, each having a separate piston 32 and piston-rod 33, each 120 piston-rod connected by a rod 34 with one end of the lever 30 of the ejectors, while each large hydraulic compression-cylinder C has the frame or head 35, Fig. 1, of its piston connected to a piston-rod 33 by a lever 36, pivoted at 37, said lever 36 being connected by a rod 38 with the piston-rod. A pipe 39 from the tank or other permanent source of hydraulic pressure communicates by a Y connection with the top of each of these cylinders. 130

ders 31. As a consequence of this location and arrangement of parts, should one compression-plunger work slightly in advance of its mate, or should the bearings between the 5 ejector-rod and compression-cylinder become worn, there will always be the same back pressure in each cylinder 31 to act against its connected compressing-cylinder. It will be understood that the valve V when 10 in position to admit water to the compression-plunger cylinder forces the compression-plungers together with a force equal to the pressure area thereof less the area of one of the pistons 32, and that when the exhaust-port 15 of the valve V is opened the pressure within the cylinders 31 acts to return the compression-plungers to their position without the mold, as is described in the prior patent referred to.

20 A portion of the framing F is inclosed to form a tank, as shown in dotted lines, Fig. 3, and is provided with numerous supporting and strengthening webs w, Figs. 2 and 4. In the bottom of the tank an endless belt or 25 conveyer T is located, passing over a sprocket s within the tank and passing out of the tank through a box B. The tank within the base or frame F extends through and up near to the top line of the bed-plate which carries the 30 tracks t t'. Through this chamber the traveling table or conveyer-belt T is located in line with ejector-plungers E and in line with a large trough-like box B, before referred to. We provide a free and unobstructed passage 35 between the lower edge of the mold which is beneath the ejector-plungers and the top of the traveling conveyer T, which conveyer we cover with a considerable depth of water, so that each block as it is forced out of its mold 40 by the ejector-plunger is dropped into the water and sinks at a comparatively slow speed, bringing up against and resting on the traveling conveyer T, by which it is removed from the tank into the box B, from which it 45 may be removed by mechanical means or by hand.

The platform T' may have plates T² depending from and adjacent to an opening for the passage of a block from the ejector reaching down toward the top of the conveyer. (See Fig. 4.) Their purpose is to prevent the scattering of loose material into the tank when a mold which has not been properly filled, and hence the contained material not 50 properly compressed, comes beneath the ejector. Such loosely-compressed material will often separate and fly out into the tank. It is our desire to pile such loose material up on the conveyer, traverse it outside of the 55 machine, and do away with the otherwise necessary draining and cleaning of the tank. Care must be taken to so proportion these plates as not to interfere with the unobstructed fall of a properly-pressed block into the 60 water-cushion and from thence onto the belt.

In order that the faces of the compression-plungers P P' may be kept well lubricated to prevent the material which is being pressed from sticking to them when compressed in the molds, we locate immediately beneath 70 the revolving mold-table M a circular or annular stationary platform T', having its upper face adjacent to and resting against the bottom edge of the molds. (See Figs. 3, 4, and 5.) This platform is so proportioned 75 that its outer and inner circumferences are free of the frame of the machine, so as to allow any particles of material which may be dropped upon it to be brushed aside and fall therefrom. The circular platform T' is preferably made of a number of different segments, such segments as come beneath the ejector-plunger and between the compression-plunger being cut away to fit said plungers, while the segment which comes beneath 80 the hopper is not so cut away. Between the hopper and ejector-plunger we locate a lubricating-box O, an opening in the platform to fit the top of the box being provided. To the under side of the traveling mold-table M, 85 near each mold, we mount a scraper 40, consisting of a loosely-swinging plate pivoted to the under side of the table M. A freely-suspended felted roller 41 is also attached to the under side of the table as to fall into the lubricating-box O as it is rotated across and above it. The radial edges of the opening in the platform T' in line with the compression-plungers are preferably formed with a slight 90 incline, so that the scraper 40 and roller 41 95 will fall into the opening and bear against the entire surface of the lower compression-plunger P', the scraper to remove any particles of material collected thereon and the lubricating-roller to lubricate the top surface of the 100 lower plunger. It will be obvious that the roller 41 not only lubricates this lower plunger-surface, but in reality lubricates the entire upper surface of the platform T', thus 105 passing over a saturated path from the time 110 it emerges from the lubricating-box O to the time it passes over the face of the plunger P'. We find it essential to locate this lubricating-box between the ejector-plunger and the feed-hopper H, for were it located anywhere else 115 the loose material within a mold as said mold passed over the lubricating-box would fall into the box and soon clog the same.

The continuous circular stationary platform T' is supported within the frame by 120 set-screws 44, passing through horizontal strengthening-webs 45 and abutting against the under side of the platform T' at their inner ends, Figs. 4 and 5, while screws 46, passing through the side of the frame, engage in 125 sockets 47, attached to the outer circumference of the platform to move the platform into adjusted positions toward or away from the common axis.

To lubricate the surface of the compression- 130

plunger P, we mount near the periphery of the table M on a hollow pivotal rod 50 an arm 51, and between each mold upon the surface of the table we locate a pin having a head 5 with inclined sides. The arm 51 has a longitudinal groove 53 open to its top surface and an adjacent interior groove 52. In the first said groove we insert a piece of felt or other material possessing capillary action with its 10 edges extending from the upper surface of the arm, so that as it is moved upon its pivot to and fro it will wipe the upstanding felted material against the face of the plunger P. Lubricant is conducted to the hollow pivotal 15 rod 50 and conveyed to the duct 52 to and throughout the length of fibrous material in the arm. The sides of the arm are formed with an incline in reverse to the incline of the sides of the screw. A weight w, passing over 20 a pulley w', is attached to the stud 50, so as to swing the arm 51 to the right upon its pivot, in which position it will be stopped by a screw-head 54. As the table rotates the screw 54 will force the arm 51 past and beneath the plunger P, lubricating the lower 25 surface of the same, and when said screw-head has been so far moved as to release the end of the arm 51 said arm will be caused to return by reason of the weight w and again 30 wipe the face of the plunger with the fibrous material, being stopped by the next succeeding screw-head 54.

In operation, save where we have herein 35 pointed out differences in operation, the improved machine of this application acts as does the machine of the prior patent, which operation, briefly stated, consists in causing two feeding-hoppers H to admit a definite quantity of material to two diametrically opposite molds in the mold-table, a connecting-rod pawl mechanism then giving the table a partial turn to bring the two filled molds beneath the compression-plungers P P', which approach the mass of material in the pair of 45 oppositely-located molds. The pawl mechanism is again operated to move the table another step to bring said diametrically opposite molds beneath the ejectors, which are operated to eject the finished block from the 50 mold, the pair of ejectors, the pair of feeding-hoppers, and the pair of compression-cylinder plungers all acting simultaneously, each on a different pair of diametrically opposite molds.

55 In this application we have merely indicated feed-hoppers, valve means, compression cylinders and plungers, and the ejector mechanism, as such elements have all been fully shown and described in the patent above 60 referred to.

Although we have shown a horizontal mold-table and a duplex arrangement of implements in this application, we do not limit ourselves to such position and arrangement, 65 as the table may occupy any position from

horizontal to vertical and the number of implements increased or diminished.

We claim as our invention—

1. An apparatus for making blocks, comprising a mold-table, molds therein, compression-plungers adapted to enter the molds, a lubricating-arm, and projections on the table to engage the arm and pass it over the face of the plungers when withdrawn from the mold. 75

2. Apparatus for making blocks, comprising a revoluble mold-table, molds therein, compression-plungers, a lubricating-arm adjacent to said table, pins on said table to engage the arm, and a counterweight, said arm 80 adapted to pass against a plunger-face upon its operation.

3. Molding apparatus, comprising a frame, a revoluble mold-table, compression-plungers, a lubricating-arm having a lubricating-duct, pivoted at one end to the frame, packing in said duct, pins on the table adapted to engage the outer end of said arm, and a counterweight to throw said arm upon its release. 85

4. Apparatus for making blocks, comprising a revoluble mold-table, molds therein, compression-plungers, a stationary platform beneath said revoluble table, and a roller pivoted to said table and traveling on said platform, and means for lubricating the roller. 90

5. Apparatus for making blocks, comprising a revoluble mold-table, molds therein, compression-plungers, a stationary platform beneath said revoluble table, a lubricating-tank in said stationary platform, and a roller pivoted to said table and traveling on said platform. 100

6. Apparatus for making blocks, comprising a revoluble table, molds therein, compression-plungers, a stationary platform beneath said table, a lubricating-tank in said platform, and a lubricating-roller pivoted to said table and traveling on said stationary platform, in combination with a scraper also pivoted to said mold-table. 105

7. Apparatus for making blocks, comprising a revoluble table, molds therein, compression-plungers, a stationary platform beneath said table, a scraper pivoted on said table and adapted to have its edge come into contact with a plunger-face as it passes over it. 115

8. Apparatus for making blocks, comprising a revoluble mold-table, a continuous circular stationary platform beneath it, lubricating-tanks in said platform, compression-plungers, said platform having openings in line with said plungers, a lubricating-arm adapted to be passed against the surface of an upper plunger, and a roller adapted to be immersed in the tank and passed over the surface of a lower plunger. 120

9. Apparatus for making blocks, comprising a pair of cylinders and plungers, a mold-table, a separate returning-lever, piston and cylinder for each plunger, an open pipe from 130

a common source of pressure to both such returning cylinders, and valved piping to the cylinders of the plungers.

10. Apparatus for making blocks, comprising a horizontal mold-table and vertical ejector means over the mold-table, a tank beneath said table adapted to contain fluid, the surface of the liquid being near to and parallel with the surface of the ejected block, so that the block falls directly and flat into the tank.

11. Apparatus for making blocks, comprising a horizontal mold-table and vertical ejector means over the mold-table, a tank beneath said table adapted to contain fluid, the surface of the liquid being near to and parallel with the surface of the ejected block, so that the block drops directly and flat into the tank.

12. Apparatus for making blocks, comprising a revoluble mold-table, compression-plungers and an ejector over the said table, a tank beneath the table adapted to contain fluid, the surface of the liquid being near to and parallel with the surface of the ejected block, so that the block falls directly and flat into the tank.

13. Molding apparatus, comprising a revoluble mold-table, plungers and ejectors therefor, a continuous platform beneath the same having openings in line with the plungers and ejectors, a tank below the table, a conveyor in the tank below its water-level, and an unobstructed passage beneath the ejectors and between the water-level and the under side of the platform.

14. Molding apparatus, comprising a frame, a revoluble mold-table, compression-plungers, a driving-shaft, a rod for intermittently grasping the table at two different points to rotate it, and a cam for driving said rod and table at a gradually-increasing, then gradually-decreasing speed.

15. Molding apparatus, comprising a frame, a revoluble mold-table, compression-plungers, a driving-shaft, a rod for intermittently grasping the table at two different points to rotate it, a cam for driving said rod and table at a variable speed, and for holding it substantially at rest, in combination with a locking means adapted to lock said table in its position of rest.

16. Molding apparatus, comprising a revoluble mold-table, notches in the periphery thereof, compression-plungers, a driving means for rotating said table, in combination with an auxiliary locking device for holding said table in a stationary position, said device comprising a shaft rotated through the driving means, and a cam on said shaft adapted to engage the notches in the periphery of the table.

17. Molding apparatus, comprising a frame, a revoluble mold-table, compression-plungers, a driving-shaft, a rod for intermittently

grasping and rotating the table, a cam for driving said rod and table at a variable speed, and for holding it substantially at rest, in combination with a notched outer edge to the table, and a rotating locking-arm adapted to register therewith in the position of rest of the table.

18. Molding apparatus, comprising a mold-table, cylinders and compression-plungers, a rod for intermittently rotating the table, a shaft having a locking-arm adapted to lock the table in its position of rest, cams on said shaft, a valve for controlling the pressure to the cylinders and levers to operate the same from said cams.

19. A revoluble mold-table, molds therein, a stationary annular platform beneath, adjacent to the lower faces of the molds, and a frame having circumferential opening for said platform.

20. A revoluble mold-table, molds therein, a stationary annular platform beneath, adjacent to the lower faces of the molds, and a frame having a circumferential opening on the outside and on the inside of said platform.

21. A revoluble mold-table, molds and tracks for the same, a stationary circular platform beneath the table of such dimension that a space will be left between the tracks and the stationary platform for the escape of the loose material.

22. A revoluble mold-table, molds passing therethrough, tracks for the table on both sides of the molds, a stationary platform beneath aforesaid table adjacent to the molds' lower faces, said table being of less width than the distance between the tracks.

23. A revoluble mold-table, molds therein, a stationary platform beneath adjacent to the lower faces of the molds, the table being so proportioned with relation to the platform as to leave a free circumferential opening around said platform, and adjusting-screws passing through the frame for adjusting the position of the platform.

24. A revoluble mold-table, trackways and molds, in combination with a stationary platform beneath aforesaid table, an ejector-plunger and compression-plungers, openings in said stationary platform in line therewith, a feed-hopper, a lubricating-box in the platform between the ejector-opening and the feed-hopper.

25. A revoluble mold-table, trackways and molds, in combination with a stationary platform beneath aforesaid table, an ejector-plunger and compression-plungers, openings in said stationary platform in line therewith, a feed-hopper, and a lubricating-box in the platform between the ejector-opening and the feed-hopper, in combination with a lubricating device depending from the revoluble table, the sides of the opening adjacent to the compression-plungers being inclined.

26. A mold-table with a recessed periph-

ery and means for intermittently revolving it, an auxiliary locking means comprising a segmental arm and means for operating it fast and slow.

5 27. A revolving mold-table, molds therein, a stationary platform beneath and against which the molds pass, said stationary platform being composed of sections secured together, and a lubricating-box opening to the 10 upper surface of said platform, in combination with compression-plungers and lubricating devices carried by the table.

28. A molding apparatus, a revoluble mold-table and means for intermittently 15 rotating it in combination with a buffer, against which said table may abut in approaching its position of rest.

29. A molding apparatus, comprising a frame, a revoluble mold-table, and a driving- 20 shaft with means for grasping the mold-table at two different points and rotate it at a gradually-increasing, then gradually-decreasing speed.

30. A molding apparatus, having an in- 25 intermittently-revolving table, in combination with a buffer, adapted to be engaged by certain points of said table when approaching its position of rest, said buffer consisting of a hydraulic cylinder and piston.

31. A molding apparatus, having an in- 30 intermittently-revolving table, in combination with a buffer, adapted to be engaged at certain points of said table, said buffer consisting of a hydraulic cylinder and piston, an 35 opening in the piston-head, and a tapered plug secured to the cylinder and fitting within said opening.

32. A molding apparatus, having an in- 40 intermittently-revolving table, in combination with a buffer, adapted to be engaged at certain points of said table, said buffer consisting of a hydraulic cylinder and piston, and a throttle means for increasing the buffer action as the piston is advanced.

45 33. A revolving mold-table having circumferentially-arranged engaging means, a hydraulic cylinder and piston, a lever secured to the piston normally having one end adapted to be engaged by the engaging means, and 50 a cam adapted to throw the lever to disengage it from said means.

34. A revolving mold-table having circumferentially-arranged engaging means, a hydraulic cylinder and piston, a lever secured

to the piston normally having one end adapted to be engaged by the engaging means, and a cam adapted to throw the lever to disengage it from said means, in combination with a tapered plug within the cylinder, passing through an opening in the piston-head, and a 60 spring adapted to return said piston to normal position.

35. In combination with the mold-ejector of a machine for molding plastic articles, a conveyer beneath said ejector and mold and plates at the lower opening of the mold and depending into the tank above the conveyer. 65

36. An apparatus for making blocks, comprising a movable mold-table, molds therein, compression means acting in said molds, a 70 roller carried by said table for lubricating the compression means, and means for lubricating the roller.

37. An apparatus for making blocks, comprising a revoluble table, molds therein, compression means acting in said molds, a lubricating-tank and a lubricating-roller carried by said table for lubricating the compression means, in combination with a scraper also 75 carried by said table to act on the compression means. 80

38. An apparatus for making blocks, comprising a revoluble table, molds therein, and compression means acting in the molds, in combination with a scraper carried by said 85 table for scraping the compression means.

39. An apparatus for making blocks, comprising a horizontal mold-table and vertical ejector means over the mold-table for ejecting the blocks therefrom, a tank beneath 90 said table adapted to contain a fluid, the surface of the liquid being near to and parallel with the surface of the ejected block so that the block falls directly and flat into the tank.

40. An apparatus for making blocks, comprising a mold-table, means for ejecting the finished blocks therefrom, and a platform supporting said table, in combination with a shield on the under side of the platform through which the blocks pass. 95

In testimony whereof we have signed our names to this specification in the presence of two subscribing witnesses.
